UNITED STATES PATENT OFFICE.

MONROE NUGENT, OF EAST QUOGUE, NEW YORK, ASSIGNOR OF ONE-THIRD TO BENJAMIN F. ROGERS, OF EAST QUOGUE, NEW YORK.

MAIL-BAG CATCHER AND DELIVERER.

No. 920,628.

Specification of Letters Patent.

Patented May 4, 1909.

Application filed September 9, 1908. Serial No. 452,172.

To all whom it may concern:

Be it known that I, MONROE NUGENT, a citizen of the United States, residing at East Quogue, Long Island, in the county of Suffolk and State of New York, have invented a new and useful Improvement in Mail-Bag Catchers and Deliverers, of which the following is a specification.

This invention relates to a device for catching and delivering mail bags, and the object of the invention is a device of this kind by means of which mail bags can be exchanged between a moving car and a stationary post or station located adjacent the track.

The invention consists in the novel features of construction hereinafter described, pointed out in the claims and shown in the accompanying drawings, in which:—

Fig. 1 is a side elevation showing the position of the parts at the time of exchange. Fig. 2 is a plan view of my device showing the position of the parts immediately preceding the exchange of mail bags. Fig. 3 is a partial side elevation of a car showing the device carried thereby and with the parts in an inoperative position. Fig. 4 is a detail sectional view illustrating the normal position of the parts carried by the car. Fig. 5 is an enlarged plan view of the outer portion of one of the bag catching arms. Fig. 6 is an edge view of the arm shown in Fig. 5 a casing carried by said arm being shown in section. Figs. 7 and 8 are detail outline views illustrating the construction of the post arranged adjacent the track. Fig. 9 is a detail view partly in section illustrating the attachment to which the mail bag is secured, a retaining cup being shown in section.

In these drawings I have shown a post formed in two sections 1 and 2 which are hinged together, and to the upper section is secured an angled lever 3 the handle portion of which projects horizontally from the rear side of the post when the same is in an upright position. By forcing said lever downwardly into the position shown in Fig. 7 the upper section of the post is swung back so that the attachment for holding the mail bag can be readily placed in position. The post is locked in this position by the lever 3, which is slotted, fitting over a suitably perforated lug 5 carried by the post section 1 and a spring gripping finger 4

carried by the lever works through a suitable opening in the lever and engages the perforated lug, thus locking the lever in its downward position. After the mail bag has been placed in position the post section 2 is 60 lifted into upright position and is then ready for exchange of mail bags with an approaching train. The hinged section 2 of the post carries upon its front face a plate 6 from which project at right angles to 65 the post upper and lower arms 7 and 8. The upper arm 7 consists throughout the outer portion of its length of a blade notched along its opposite sides as shown at 9, the notches being semi-circular in form and the 70 upper portion of the blade lying between said notches forms upon each side of the blade a series of arrow heads 10 each of which is provided upon its opposite sides with inwardly extending fingers 11 bent at 75 their inner ends to form hooks, and which hooks project into the notches 9 and prevent accidental withdrawal from said notches of any article which may have entered them. The blade 7 and the fingers 11 may be formed 80 of spring steel or any other suitable material.

At its extreme outer end the arm 7 carries a cylindrical casing 12 from the top of which depends a pin 13 about which is a coil spring 14. A plunger 15 works in the 85 casing 12 and is suitably recessed at its inner end to receive the spring 14. The lower outwardly extending end portion of the plunger 15 is provided with a concaved face forming an inverted cup 16. By reducing this lower portion an annular shoulder 15^a is formed on the plunger, which when in its lowest position rests upon a flange formed at the lower end of the casing 12. The lower arm 8 of the post section 2 95 is merely a plain smooth arm but at its upper end carries a block having a recessed upper face which forms a cup 17, below and in vertical alinement with the inverted cup 16.

The attachment holding the mail bag consists of a straight rod 18 each end of which is provided with a convex head 19 and these heads rest respectively in the cups 16 and 17 when the attachment is in place. The combined lengths of the rod 18 and heads 19 is such as when fitted into position the plunger 15 is forced upwardly and inwardly against the tension of the spring 14, and the pressure of this spring locks the rod 18 securely in 110

place but as the cups 16 and 17 are comparatively shallow, any force sufficiently strong to further compress the spring 14 will draw the rod 18 and the heads 19 away 5 from said cups. The rod 18 adjacent its lower end is provided with a right angled red 20 to the free end of which is secured a stirrup 21 to which is hooked or otherwise secured a mail bag 22.

10 The appliance carried by the car is practically a duplicate of that carried by the post section 2 with the parts reversed. The car attachment consists of a vertically rotatably mounted shaft 23 having at its lower end a 15 cranked portion 23^a. This shaft 23 carries an arm 8^a which at its outer end carries a cylinder 12^a. The cylinder 12^a corresponds in construction and use with the cylindrical casing 12 of the post attachment, but in the car 20 apparatus it is carried by the plain arm instead of the notched blade. Below the arm 8^a the shaft 23 is provided with an arm 7^a which corresponds to the arm 7 and which carries at its outer end a cup 17^a corresponding 25 to the cup 17 of the arm 8. These parts normally rest just inside the car door and in order to swing them outwardly the rod 24 is pivotally connected to the angled crank portion 23^a and is also provided with racked 30 teeth 25. These teeth are engaged by a segmental gear 26 to which is connected an operating lever 27. By throwing the said lever into downward position the rod 24 is shifted longitudinally this giving a partial 35 rotation to the shaft 23 and swinging the arms 7^a and 8^a outwardly at right angles to the car, and parallel to the arms 7 and 8 which the car is approaching. The parts are so arranged that as the car passes the 40 sectional post the arm 8^a of the car will pass above the arm 7 of the post while the arm 7^a of the car will pass between the arms 7 and 8. The mail bag to be delivered from the car is secured to the arms 7 and 8 45 by means of an attachment similar to that shown in Fig. 9 already described.

It will be obvious that as the car passes the rod 18 carried by the car will be caught by one of the notches of the blade 7 and 50 will be disengaged from the arms 7^a and 8^a and the rod will remain in the notch 9 in which it is caught, the upper head 19 being too large to permit the rod 18 slipping downwardly through said notch. In like 55 manner the rod 18 carried between the cups 16 and 17 will be caught by the notched blade 7^a of the car from which it can be withdrawn by the operator when the parts have been returned to their normal 60 positions.

What I claim is:—

1. A device of the kind described consisting of two parallel arms, one of said arms being provided with notches, a cup carried by one of said arms, an inverted vertically movable spring pressed cup carried by the other arm, a rod, heads carried by the rod and adapted to be seated in said cups, and means for supporting a mail bag carried by said rod, the notches of one of the arms receiving and holding a similar rod carried by a cooperating device. 65

2. A device of the kind described comprising a fixed and a movable mail bag holder, each of said holders consisting of two parallel arms, one of said arms being notched, a cup carried by one of said arms, a cylindrical casing carried by the other arm, a spring in said casing, a movable cup held in the casing and pressed upon by said spring, rods having convex heads, the heads fitting in said cups, one of said rods being carried by the stationary and one by the movable devices, and means for securing a mail bag to each of said rods. 70

3. A device of the kind described consisting of parallel arms, a stationary post supporting said arms, the upper arm being notched, an inverted spring pressed vertically movable cup carried by the outer end of the notched arm, a fixed cup carried by the other arm, mail bag holding means seatable in said cups, a rotatable shaft vertically arranged upon a car, means for rotating said shaft, parallel arms carried by the shaft, the lower arm being notched and in a horizontal plane between the arms of the post, an inverted spring pressed vertically movable cup carried by the upper arm of the car, a fixed cup carried by the notched arm of the car, and mail bag holding means held between said cups, the holding means of the car being caught by the notched arm of the post, and the holding means supported by the post being caught by the notched arm of the car. 95

4. A device of the kind described comprising parallel arms arranged adjacent a track, parallel arms carried by a car, the arms of the car being offset with respect to the first mentioned arms, and mail bag holding means carried between the outer ends of each set of arms, one arm of each set being notched to engage and receive the mail bag holding means of the other set. 100
